ATTORNEY.

UNITED STATES PATENT OFFICE

WILLIAM R. ROSE, OF ARLINGTON RIDGE, VIRGINIA

FLASHING FOR ROOFS

Application filed June 14, 1930. Serial No. 461,182.

The invention relates to flashings for roofs, particularly to sectional flashings adapted to general uses, and especially to one valuable for use on fabricated roofs made of felt sheets or the like with a binder of bituminous material usually applied hot. It is an important object to present an improved flashing of that type which includes a member adapted to be built into a wall, or to be otherwise engaged permanently in a building structure, and a movable section adapted to extend downwardly over the building structure and an upturned lateral portion of a roof, and which during construction of the roof may be itself turned upwardly so as to lie out of the way and not obstruct operations in building of the roof thereto.

It is a special object to present a novel construction and coordination of the mutually connecting parts of the permanently fixed member and the movable part. A particular object is to effect a construction in the two parts whereby they may be brought together into operative relation by a simple pressing together of the two members, yet insuring their permanent retention in operative relation when one member is properly fixed on the building. Another object is to improve the coaction of the two members so that the movable member will be held automatically in raised or non-obstructing position, and whereby under a simple movement of the parts the movable member may be moved to and retained in operative position.

Another object is to simplify the forms of the parts to the ends that they may be readily manufactured by simple shop operations, and produced from stock materials commonly available commercially.

Additional objects, advantages and features of invention reside in the construction, arrangement and combination of parts involved in the embodiment of the invention, as may be more readily understood from the following description and accompanying drawing, wherein,

Figure 1 is a fragmentary cross section of a brick wall in which my flashing is incorporated, the movable member being raised.

Figure 2 is a similar view with the mov-

able member lowered and secured in operative relation to a roof.

Figure 3 illustrates the detail of the corner construction in elevation from one side.

Figure 4 illustrates the manner of incorporating my flashing in a Portland concrete moulded structure.

Figure 5 illustrates a modified use of the invention.

There is illustrated a portion of a building 60 10, which—as in Figure 1—may be of brick 11 laid in horizontal courses with mortar joints 12 therebetween. The flashing comprises the anchor or upper member 14, and a swinging member 15, both formed of sheet 65 metal such as galvanized iron or nonferrous metal. The anchor member 14 has a broad flange 15 laid in the mortar between two brick courses as the structure 10 is erected, although it may of course be inserted afterward by 70 gouging out a suitable channel in the joint, introducing freshly mixed mortar, and inserting the flange as required. The flange 16 comprises a major top portion of the anchor member the outer part 16' of which is inclined downwardly at a slight angle sufficient to readily shed water and drain the same away from the wall surface thereadjacent. At its outer edge the material of the anchor member is bent downwardly at right angles 75 forming an outer wall 17, thence inwardly at right angles forming a bottom flange 18, and thence upwardly and outwardly at an angle of about 95 degrees or more, forming a heel 19' at the bend, and a terminal upwardly inclined flange 19, the lines of the last three bends being equi-distant from each other, although this may not be essential. The upturned portion 19 stops short of the outer top part 16 a distance, being of much less extent 80 from the bend than the distance between the lines of bend last mentioned. The upturned flange 19 is spaced at its bottom very close to the face of the wall, and indeed may tend to rest against the face of the bricks, if desired.

The swinging or movable member 15 comprises a depending portion of much greater extent ordinarily than that of the anchor member, depending on the height of flashing 100

required or desired. Its lower part 20 extends inwardly at an angle to the wall while its upper part 21 may extend approximately parallel to the wall. With the major or lower portion hanging pendant against the wall, 5 the upper edge portion extends upwardly between the flange 19 and the wall of the building at 22', then extends at right angles outwardly over the flange 19 a distance as at 22. Thence it is continued at 23' downwardly 10 at an angle of about 70 degrees in spaced relation to the wall 17 of the upper member, forming a terminal sealing flange 23 which is of greater altitude than the flange 19 so that it rests directly upon the bottom flange 18. 15 The top flange part 22 of the bottom member 15 is of a width approximately the same as that of the bottom flange 18 and the altitude of the flange 19 is considerably less. By 20 this, when the lower piece 15 is swung outwardly and upwardly the part 22 becomes engaged between the heel 19' and the wall, the part 22 extending a distance below the heel 19' and is thereby pressed against the 25 face of the wall so as to support the major portion of the member 15 in outwardly extending position as in Figure 1. Likewise, when the member 15 is lowered, the heel 19' presses inwardly against the lower member 15, causing the extremity of the lower member to lie snugly against the wall. When the 30 movable member is shifted from one position to the other, the upper member 14 is slightly sprung from initial position on the wall until 35 the swinging member 15 is moved into such position that a flat part thereof may be confined between the heel 19' and the wall, when the heel 19' springs back to initial position.

When the roof has been laid and the lower 40 flashing piece 15 is moved downwardly, the pressure of the heel 19' against the part below the anchor member 14 will be sufficient to hold the extreme lower edge of the lower flashing piece 14 against the upturned parts 45 of roofing, so that it will not be disturbed by winds or displaced by rodents. But if so desired a simple wedge device 40 may be inserted over the member 15 so as to extend between the heel 19' and the lower member 50 15, whereby the latter is pressed with greater force against the wall, especially at the lower part.

The functioning of the device without the wedge has the advantage that the parts are 55 held securely enough to preserve them against loose movement and to prevent rattle and noise by winds or building vibrations of ordinary kinds. The last named features are quite material in assuring long life and service of the flashing.

In building the anchor member into a brick wall, the wall is constructed in the usual way to a height slightly above that to which it is desired to have the flashing extend. A 60 complete course of bricks being laid, a thin

layer of mortar is applied on top of such last course, after which the flange 16 of my anchor member is laid upon the mortar, while the heel 19' is set as close as practicable to the outer surface of the wall. At 65 this time the member 15 is preferably in lowered position, a prop or other means is then employed to hold the heel 19' snugly against the wall while the mortar sets. It may be found desirable to crimp or otherwise distort the edge of the flange 16 in the wall so that it may not readily pull out of place. It is not essential that the prop or other means be employed to hold the heel 19' forcibly against the wall while the device 70 is being set in the wall, but the lower part of the member 15 may be simply laid lightly against the wall. Then when the roof is applied and brought up beside the wall to be covered by the flashing, the thickness of 75 the roof material will hold the flashing member 15 still further outward and result in pressure by the heel 19' thereagainst as indicated.

In setting the flashing in a concrete wall, 80 the planks of the form may be separated at the point where the flashing is to go, sufficiently to permit the outer flange and the bottom flange 18 to fit snugly between them, while the flange 16 projects into the form. 85 The flashing may be secured temporarily to the form by some approved means if desired.

The corner fittings may be made in accordance with approved practices which will be readily understood by cornice workers and roofers. I have found it practicable to join two short lengths of the anchor from two sides of a wall, as a right angle fitting which may be set in place as a unit. But for the lower members coordinated therewith, I may 90 simply cut off a portion of the flange 22-23, leaving only the lower body portion of the members 15 where they underlie the right angle fitting. The projecting ends may then be bent around the corner of the wall in 95 overlapped relation, and "tack soldered" or held by wedges at the upper parts as before mentioned.

It will be noted that while the aggregate vertical measurement of the parts 19 and 23 100 is greater than the distance from the part 16' to the flange 18, still when the two parts have been formed and are to be brought together, this may be done by simply presenting the part 22 against the under side of the 105 part 18 and then pressing the flange 23 outward and against the inclined flange 19, the two yielding to and sliding on each other until the top part of the member 16 is properly entered in the top member 14.

It is also possible to keep the parts separate while the upper or anchor member is built into the wall, and then—after the mortar has set—the member 15 with its major part horizontal as shown in Figure 1, may 110

be presented beneath the flange 18, and the flange 23 pressed upward behind the heel 19' until the one snaps over the other and the heel springs outward against the part 22 as shown in Figure 1.

5 When made in galvanized iron (which is largely used for flashings) the spring action of the heel 19' is quite positive and not liable to impairment, on account of the inherent resilience of the material as customarily manufactured, notwithstanding that the material is readily bent to the forms desired. In soft copper the action would still be found, though more care is required in handling the 10 material to avoid deformation.

15 I claim:

1. A two piece flashing comprising an upper member having a body adapted to be set in a wall and having a downturned and in-turned outer edge the extremity of which is 20 presented inwardly as a presser heel tending to engage a wall in which the member is set; and a lower member swingingly mounted on the first, the swinging connection consisting 25 of an outwardly and downwardly turned edge portion having a flat part arranged to be engaged by said heel and pressed against a supporting wall when the lower member is 30 swung upwardly to inoperative position, the downturned part of the lower member arranged to rest upon the inturned part of the upper member and hold a substantial part of the lower part of the member extending above the heel when the parts are in operative position, 35 whereby the bottom member is then pressed against the wall by said heel as described.

2. A flashing of the character described comprising an anchor member having a flange 40 portion adapted to be set in a wall or the like, its outer part being bent downwardly, then inwardly, and its terminal edge being arranged as a presser heel; and a swinging member having an upper edge portion pressed 45 upon by said heel and extended above and bent outward at a sharp angle above the heel, its terminal edge being shaped for retaining engagement with the heel.

3. A flashing of the character described 50 comprising an anchor member having a body portion adapted to be set in a wall or other structural element its outer part being bent downward spaced outward from the plane of the wall face, then bent inward spaced below 55 the body and then bent upwardly on a line at said plane to form a presser heel, the extremity of the last named upwardly bent portion stopping short of the first named body portion a distance; and a swinging member 60 adapted to lie against a wall having an upper edge portion bent outwardly at a sharp angle to form a flat extending over the last named part of the anchor member, and then being bent downwardly at a sharp angle spaced 65 from the first named downturned part of the

anchor member and extended a distance greater than the space between the body and up-turned part of the anchor.

4. In a flashing of the character described, 70 an upper anchor member having downturned and inturned outer edge portions, and a lower swinging member having outturned and downturned upper edge portions set within said outer portions of the anchor member as a pivot, said swinging member having angularly disposed flat parts adjacent the pivot positioned to lie alternately against an engaged wall by pivotal adjustment, said outer portions of the anchor member having an extreme part positioned to yieldingly interlock 75 at respective positions with the flat parts, whereby to oppose yieldingly relative pivotal movement of the anchor and swinging members at operative and inoperative positions.

5. The structure of claim 4 in which the 80 anchor member has an upturned outwardly inclined extreme edge portion, the downturned part of the swinging member is inclined inwardly and the aggregate vertical dimensions of the upturned part of the anchor 85 member and the downturned part of the swinging member exceed the vertical distance between the body of the anchor member and the inturned part thereof, whereby when pressed laterally together the extreme edge 90 portions yieldingly coengage and slide upon and past each other, and prevent reverse separating movement.

In testimony whereof I affix my signature.
